UNITED STATES PATENT OFFICE.

EUGENE HIGGINS, OF BATTLECREEK, MICHIGAN, ASSIGNOR TO THE DUPLEX PRINTING PRESS CO., OF BATTLECREEK, MICHIGAN.

PRINTING-PRESS.

SPECIFICATION forming part of Letters Patent No. 700,119, dated May 13, 1902.

Application filed July 19, 1901. Serial No. 68,921. (No model.)

To all whom it may concern:

Be it known that I, EUGENE HIGGINS, of Battlecreek, in the county of Calhoun and State of Michigan, have invented certain new and useful Improvements in Printing - Presses; and I hereby declare that the following is a full, clear, and exact description thereof, reference being had to the accompanying drawings, which form part of this specification.

This invention is an improvement in printing-presses, and has particular reference to stationary-bed movable-cylinder web-printing presses—such as the well-known Cox duplex press, for example—its object being to prevent the cylinder grinding the type or rupturing or cracking the web during impressions; and this object is attained by the simple means illustrated in the accompanying drawings and hereinafter claimed and is applicable to any form of bed-and-cylinder press, requiring no additional parts. It has been ascertained that in this class of presses the cylinder if overpacked has a tendency to move faster on the type and grind the same, or if under-packed has a tendency to lag or drag on the type and grind the same, this grinding occurring frequently in presses where the cylinder and bed are geared together so that the cylinder must rotate at a certain ratio during impressions, the gearing ordinarily being calculated on the basis of having the cylinder packed so that its diameter will exactly correspond with the pitch-line of the cylinder-gear. When so packed, no injury will result to the type or web; but this theoretical accuracy is seldom attained in making up the cylinder, and as the gearing remains constant any variation in the circumference of the cylinder due to overpacking or underpacking produces the drag on the type above mentioned, and this drag or crawling of the periphery of the impression-cylinder on the type tends to shift the paper over the type while nipped in impression, resulting frequently in cracking and rupturing the web.

The principal objects of the bed-and-cylinder gearing in movable-bed presses is to insure that the periphery of the cylinder be moving uniformly with the type when the impression begins and that the proper portion of the cylinder-packing shall always contact

with the type, and in reciprocating-cylinder stationary - bed presses the gearing is employed to assist in slowing down, stopping, and reversing the rotation of the cylinder without letting it unduly "comb" upon the web or slide onto the type. It is therefore necessary that the gearing shall be of proper full proportion at the ends of the rack or strokes; but it is practically possible to reduce the intermediate gear - teeth, thus widening the space between them, so that when the cylinder is on impression it is permitted a certain slight amount of play relative to the rack sufficient to permit its periphery to move accurately over the type without pulling or dragging thereon, allowing the cylinder to compensate itself for over or under packing, while by gradually merging the reduced gear-teeth into the full-sized gear-teeth near the ends of the rack or travel of the cylinder the latter will be always started and stopped in exact proper position and time without rattle or jarring.

The invention consists simply in making certain of the teeth in the gearing between cylinder and bed smaller than normal-sized teeth, thus widening the spaces between such teeth, so as to permit the periphery of the cylinder to move slightly faster or slower during impression than it would otherwise do if the teeth of the gearing and distance between teeth were uniform throughout, the gearing being so formed for the purpose of compensating for improper packing of the impression-cylinder and effecting the desired results in a simple inexpensive manner.

In the drawings, Figure 1 is a detail side elevation of a bed-and-cylinder press. Fig. 2 is a top plan view of Fig. 1.

A designates an impression-cylinder adapted to coact with type on bed K and having bearers C coacting with bearers D on frames G and a cylinder-gear F coacting with a stationary rack E on the frame G, all substantially as usual. The packing B of the cylinder should correspond with the pitch-line of gear F, as indicated in Fig. 1; but this theoretically and practically important condition is seldom attained, owing to carelessness of the pressmen. Consequently the evil effects of overpacking or underpacking the cylinder

der above pointed out are produced. To prevent this improper packing of the impression-cylinder damaging the type or rupturing the web, the teeth of the rack E, which would 5 control the cylinder during impression, (indicated between the lines TT on the drawings,) are made much thinner than necessary to maintain perfect mesh, the widened spaces between these thin teeth permitting a certain 10 amount of play of the periphery of the cylinder, so that it is practically left free to rotate by contact with the type while on impression, thus avoiding dragging or lagging on the type or web. Between the points T and S at 15 each end of the bed the teeth are gradually increased in thickness, so as to take up without any sudden shock or jar any crawling forward or lagging of the cylinder between the points TT during impression due to improper 20 packing of the cylinder. Between the points S and R the teeth are of full size, so that the cylinder is brought to a stop and reversed properly.

When the cylinder engages with the thick 25 teeth of the rack and moves from position A² in the direction of the arrow U, it is caused to revolve in the direction of the arrow V, as shown in Fig. 1.

As the cylinder rolls upon the type the 30 gear F engages with the thin teeth of the rack. If the cylinder be overpacked or underpacked, it will when on the type tend to move faster or slower than its normal rate. As the spaces between the teeth in this part 35 of the rack are wider than the thickness of the teeth on the gear, the cylinder will be permitted to so revolve, and its tendency to crawl or drag upon the type and the consequent wear is prevented. After the cylinder 40 leaves the type and is free from surface contact therewith the gear again engages with the gradually-thickening teeth at the opposite end of the rack, and before reaching the end of its stroke the position of the cyl-

inder is corrected. The same operation takes 45 place during the return stroke of the cylinder.

As the play allowed between the gear F and rack E by reason of the shape of the teeth of the latter is very limited, the mechanism 50 will be operative in the manner described only to a correspondingly-limited degree, sufficient, however, to correct the tendency of the cylinder to drag or crawl on the type.

Having thus described my invention, what 55 I therefore claim as new, and desire to secure by Letters Patent thereof, is—

1. The combination of a cylinder, its gear, a bed coacting with the cylinder and a bed-rack meshing with said gear, the teeth of the 60 rack being irregular to permit play of the cylinder relatively to the rack while on impression, substantially as described.

2. The combination of a cylinder and bed, the cylinder-gear, and the bed-rack coacting 65 with said gear, said rack having its intermediate teeth thinner than its end teeth, and the spaces therebetween correspondingly wider, for the purpose and substantially as described.

3. The combination of a cylinder and bed, the gear on the cylinder and a bed-rack meshing therewith having its teeth opposite the type-forms on the bed reduced in thickness, and the spaces therebetween increased to permit play of the cylinder relatively to the gear 70 while on impression, the teeth of the rack beyond the forms increasing to full size to correct any lost motion or accelerated movement of the cylinder during impression, substantially as and for the purpose set forth.

In testimony that I claim the foregoing as my own I affix my signature in presence of two witnesses.

EUGENE HIGGINS.

In presence of—

RICHARD L. STOUT,
F. W. DUNNING.
